UNITED STATES PATENT OFFICE

SAMUEL S. RIEGEL, OF SCRANTON, PENNSYLVANIA

LATERAL MOTION DEVICE FOR LOCOMOTIVES

Application filed March 17, 1928. Serial No. 262,478.

This invention relates to lateral motion devices for locomotives and has for its primary objects the provision of a device of this kind which is simple and rugged in construction, positive in operation and easily assembled and adjusted to compensate for wear or to accommodate it to varying track or operating conditions.

A further object of the invention is the provision of a structure of this character all the parts of which are readily accessible from the inside of the locomotive frame without lifting the frame from the axles.

More specifically my invention contemplates a lateral motion device which is constructed to resiliently urge the axle with its driving boxes toward the middle or normal position.

Still more specifically I contemplate the provision of a lever mechanism which engages some part of the driving box structure and which is spring pressed to resist relative lateral motion between the box and the locomotive frame.

How the foregoing together with other objects and advantages are obtained will be clear from the following description considered in connection with the accompanying drawings which illustrate a convenient embodiment of the invention.

Fig. 1 is a view in elevation of a portion of a locomotive side frame with my improved lateral motion device applied thereto, the view being taken from the inside of the frame and the driving box proper being omitted for the sake of clarity;

Fig. 2 is a sectional view through a pedestal jaw of the frame and the mechanism of the present invention, taken substantially on the line 2—2 of Fig. 1, a portion of the axle and box proper being shown in this figure; and

Fig. 3 is a sectional view taken through the frame and the device as indicated by the line 3—3 of Fig. 1.

Referring now more particularly to the drawings the side frame is indicated by the reference character 4, the same being provided with pedestal jaws 5 between which the driving box 6 (Fig. 2) is adapted

to be mounted. A pedestal binder 7 secures the pedestal jaws together and retains the box therebetween.

A wear compensating wedge 8 may be provided on the inner face of one of the jaws 5, the same generally being provided with an adjusting stem or rod 9 extending downwardly through an aperture in the pedestal binder 7. The pedestal jaws (with or without the wedge 8) are preferably embraced by the flanges 10 of pedestal shoes 11, and it should be noted at this point that the flanges 10 do not snugly embrace the pedestal jaws, but are spaced to provide the clearance for lateral motion indicated at 12 (Figs. 2 and 3). The box 6 is provided with flanges 13 which embrace the shoes 11, their flanges 10 and the jaws 5, and it should also be noted that the box is provided on its outer side with a surface 14 adapted to receive the lateral thrust from the hub 15 of the wheel 16, the latter, of course, being mounted on the axle 17 which is journaled in the box.

On either or both sides of the box I provide a mechanism which is adapted to resiliently resist lateral motion of the box structure and the axle with respect to the locomotive frame. This mechanism is constructed as follows:

A member or lever, generally indicated by 18, is provided with a spring pocket or seat 19 which is preferably arranged to extend vertically along an edge of the box. This member has two arms 20 which extend from the pocket 19 away from the box and which are mounted on a common pivot pin 21. Upper and lower brackets or lugs 22 and 23, respectively, are secured to the locomotive frame and are provided with apertured upstanding lugs 24 adapted to receive and provide a bearing for the ends of the pin 21. The bracket 22 may be provided with a strengthening lug 25 protruding therefrom and engaging the under surface of the upper member of the locomotive side frame 4 (Fig. 1). The brackets 22 and 23 may be secured to the frame 4 in any suitable manner as by bolts 26.

A bracket member 27 is pivoted on the

pin 21 between the arms 20 and is constructed and configured in such a manner that its free end 28 overlies the spring pocket 19 of the lever 18. A spring 29, preferably of the "leaf" type, is positioned to react between the members 18 and 27, its ends 30 being seated in the pocket 19 and its band 31 being seated in the end portion 28 of the bracket 27.

10 The bracket 27 is tied to the frame by means of bolts 32 tapped into the pedestal jaw 5, the bolts being provided with nuts 33 which may be used to adjust the tension of the spring 29.

15 At its swinging or free end, beyond the pocket 19, the member 18 is provided with a lip or tongue 34 which is extended to engage some part of the box structure and receive the lateral thrusts therefrom. In the 20 particular embodiment illustrated in the drawings this tongue or extension 34 extends between the shoe and box flanges 10 and 13, respectively, to engage the former and receive the lateral thrust. However, it is 25 quite obvious that the tongue 34 could be arranged to receive the thrust from a number of different parts of the box structure, as, for example, the inner face 35 of the box itself.

30 A bolt or set screw 36 is provided in each arm 18 and is adapted to abut against the pedestal jaw. It serves to space or adjust the tongue 34 with respect to the flange 10 of the shoe 11. Preferably this adjustment 35 is set to provide a very small clearance, say one-sixteenth of an inch, between the adjacent surfaces of the tongue and the flange 10 (see 37, Fig. 2).

35 In considering the operation of my invention it must, of course, be borne in mind that both of the boxes for any particular axle adapted for lateral motion will be provided with my improved lateral motion resisting mechanism and that the mechanism on each 40 side is mounted at the inside of the locomotive side frame members. Thus, when a track curve or some other road condition causes an axle movement inward from one 45 side the mechanism on that side will come into action and will resist the lateral motion and tend to return the axle to mid or normal position with respect to the frame. If 50 the thrust is inward from the other side, of course, the other resisting mechanism 55 operates.

55 My invention, therefore, contemplates a lateral motion resisting mechanism which is very positive in operation and one which is easily assembled or repaired and capable 60 of convenient and effective adjustment.

I claim:—

1. A lateral motion device for locomotive driving boxes including a lever pivoted at one end to the locomotive frame, the other 65 end being free to swing toward and away

from said frame and being adapted to engage the box structure and spring means for urging the swinging end of said lever toward said frame, together with means for limiting the swing of said lever toward the 70 frame and means for adjusting the tension of said spring means.

2. In a locomotive, the combination of a pair of pedestal jaws, a driving box mounted therebetween with freedom for a limited 75 amount of lateral motion, a lever pivoted at one end to the locomotive frame and extended to engage the box structure and spring means reacting against said lever to resiliently retain said box substantially at 80 one limit of its motion.

3. A lateral motion device for locomotive driving boxes including a lever pivoted at one end to the locomotive frame and extended to engage the box structure and 85 spring means cooperating with said lever to resiliently resist lateral motion of the box.

4. In a locomotive the combination of a pedestal jaw, a box shoe having flanges constructed and spaced to embrace the jaw and provide a limited lateral movement relative thereto, a driving box having flanges embracing said shoe flanges, a member pivoted to the locomotive and extending between a box and a shoe flange to engage the latter 90 and means for resiliently resisting lateral movement of said member.

5. In a locomotive the combination of a slide frame having pedestal jaws, a driving box structure mounted between said jaws 100 with freedom for lateral movement relative thereto, a pair of coaxially pivoted members, the swinging end of one of said members engaging the box structure and the swinging end of the other being adjustably secured to 105 said frame, and spring means reacting between said members to resiliently resist lateral movement of said box structure.

6. A lateral motion device for locomotive driving boxes including a lever pivoted at 110 one end to the locomotive frame and engaging the box structure at its other end, a bracket secured to the frame and spring means reacting between the bracket and the lever at a point intermediate its ends.

7. A lateral motion device for locomotive driving boxes including a lever pivoted at one end to the side of the locomotive frame and engaging the box structure at its other 120 end, a bracket secured to the said frame and overlying the said lever and spring means reacting between the lever and the bracket.

8. A lateral motion device for locomotive driving boxes including a lever pivoted at 125 one end to the locomotive frame and engaging the box structure at its other end, a bracket secured to the frame and spring means reacting between the bracket and the lever at a point intermediate its ends, to- 130

gether with means for limiting the movement of the lever.

9. A lateral motion device for locomotive driving boxes including a lever pivoted at one end to the locomotive frame and engaging the box structure at its other end, a bracket secured to the frame and spring means reacting between the bracket and the lever at a point intermediate its ends, together with adjustable means for limiting the movement of the lever.

10. A lateral motion device for locomotive driving boxes including a lever pivoted at one end to the locomotive frame, the other end being free to swing toward and away from said frame and being adapted to engage the box structure and spring means for urging the swinging end of said lever toward said frame, together with means for 20 adjusting the tension of said spring means.

11. A lateral motion device for locomotive driving boxes including a lever pivoted at one end to the locomotive frame and engaging the box structure at its other end, a 25 bracket member overlying the lever and a leaf spring reacting between the lever and the bracket member to resist lateral motion of the box.

12. A lateral motion device for locomotive driving boxes including a lever pivoted at one end to the locomotive frame and engaging the box structure at its other end, said lever being provided with a pair of spaced spring seats, a bracket member overlying the lever and a leaf spring with its ends in said seats and an intermediate portion engaging the bracket member to resist lateral motion of the box.

13. In a locomotive, the combination of 40 frame and driving box members relatively movable laterally with respect to each other and means for resisting the relative lateral movement including a member movable with the driving box, a member movable with the frame, one of the two last mentioned members overlying the other at a side of the frame member and spring means positioned and re-acting between the members overlying each other.

14. In a locomotive, the combination of 50 frame and driving box members relatively movable laterally with respect to each other and means for resisting the relative lateral movement including a member pivoted at one end to the frame member and extended to engage the box structure at its other end and spring means of substantially constant resistance value at a given relative lateral position of the frame and box irrespective of the relative vertical position and acting on said pivoted member to resist said relative lateral movement.

15. In a locomotive, the combination of 60 frame and driving box members relatively movable laterally with respect to each other

and means for resisting the relative lateral movement including a member pivoted at one end to the frame member and extended to engage the box structure at its other end and spring means of substantially constant resistance value at a given relative position of the frame and box and acting on said pivoted member to resist said relative lateral movement, together with means for adjusting the resistance value of the spring means.

16. In a locomotive, the combination of 70 frame and driving box members relatively movable laterally with respect to each other and means for resisting the relative lateral movement including a member pivoted at one end to the frame member and extended to engage the box structure at its other end and spring means of substantially constant resistance value at a given relative lateral position of the frame and box irrespective of the relative vertical position and acting on said pivoted member to resist said relative lateral movement, together with stop means limiting pivotal movement of said member.

17. A lateral motion device for locomotive 80 driving boxes including a lever pivoted at one end to the locomotive frame and engaging the box structure at its other end and spring means acting on said lever to resist lateral motion of said box, said spring means being operable independently of the support of the locomotive on the box.

18. A lateral motion device for locomotive 90 driving boxes including a lever pivoted at one end, on a substantially vertically disposed axis, to the locomotive frame and engaging the box structure at its other end and spring means acting on said lever to resist lateral motion of said box.

19. A lateral motion device for locomotive 100 driving boxes including a lever pivoted at one end, on a substantially vertically disposed axis, to the locomotive frame, the other end being free to swing toward and away from said frame and being adapted to engage the box structure and spring means for urging the swinging end of said lever toward said frame.

20. A lateral motion device for locomotive 110 driving boxes including a lever pivoted at one end, on a substantially vertically disposed axis, to the locomotive frame, the other end being free to swing toward and away from said frame and being adapted to engage the box structure and spring means for urging the swinging end of said lever toward said frame, together with means for limiting the swing of said lever toward the frame.

21. In a locomotive the combination of a pair of pedestal jaws, a driving box mounted therebetween with freedom for lateral movement, a lever pivoted at one end to the locomotive frame and engaging the box 130

structure at its other end, and spring means acting on said lever to resist lateral movement of the box, said spring means being of substantially constant resistance value at a given relative lateral position of the box and jaws irrespective of the relative vertical position.

In testimony whereof I have hereunto signed my name.

SAMUEL S. RIEGEL.
